JOHN MARTINO, JACOB BEESLEY, AND JOHN CURRIE, OF PHILADELPHIA, PENNSYLVANIA,
ASSIGNORS TO MARSHBANK & MARTIN, OF LANCASTER, PENNSYLVANIA.

Design No. 2,687, dated June 25, 1867.

DESIGN FOR A COOK'S STOVE.

The Schedule referred to in these Letters Patent and making part of the same.

TO ALL WHOM IT MAY CONCERN:

Be it known that we, JOHN MARTINO, JACOB BEESLEY, and JOHN CURRIE, of the city of Philadelphia, in the county of Philadelphia, and State of Pennsylvania, have originated, designed, and produced a set of new Patterns for a Stove, called the Nimrod, manufactured by Marshbank & Martin, Lancaster, Pennsylvania, as represented by a wood-cut, taken from a photograph of the same, which gives a full, clear, and exact representation thereof, and is hereunto annexed, forming a part of this specification, showing the configuration and ornamental design and lettering clearly illustrated.

What we claim as our invention, and desire to secure by Letters Patent, is—

The design or pattern of said cook-stove as herein described and shown.
